UNITED STATES PATENT OFFICE

DIDRICK DYRESEN, OF MALDEN, MASSACHUSETTS

SEPARABLE FASTENER

Application filed March 6, 1926, Serial No. 92,719. Renewed February 2, 1928.

This invention aims to provide improvements in separable fasteners.

In the drawings, which illustrate a preferred embodiment of my invention:—

Figure 1 is a front elevation of the preferred form of fastener;

Fig. 2 is a section on the line 2—2 of Fig. 1, being partly in elevation;

Fig. 3 is a section similar to Fig. 2, but showing initial movement of the depending finger by movement of the curtain relative to the stud;

Fig. 4 is a plan view of the socket-engaging part of the stud prior to assembly with the rest of the stud; and

Fig. 5 is an elevation view of the part shown in Fig. 4.

Referring to the form of my invention illustrated by the drawings, I have shown a three-side lock fastener which is similar in construction and operation to the fastener illustrated and described in my co-pending application Serial No. 92,718, filed herewith.

The socket illustrated includes a one-piece casing 1 formed in the same manner and secured in the same manner by a screw 2 to a rigid support 3 to provide a flush type fastener as more fully described in the above-mentioned application. The only difference in the socket shown in Figs. 2 and 3 of this application is the formation of the closure plate 4 which in this instance is provided with an embossed portion 5, the purposes of which will be hereinafter described.

The stud member illustrated includes the socket-engaging part 6, the front plate 7, the attaching means and the latch-presenting part 8 or lever, all of which, except the socket-engaging part, are substantially the same as illustrated and described in the above-mentioned application. In this instance, the socket-engaging part 6 is non-resilient and of a diameter which is the same or slightly smaller than the stud-receiving aperture 9 presented by the socket. A slot 10 is provided at the upper side of the socket-engaging part 6 through which the latch 11 operates. The outer end of the socket-engaging portion is preferably reduced to facilitate entrance of the stud into the socket and the wall

at the outer end is pressed inwardly to provide a recess or aperture surrounded by a wall 12, as shown in Figs. 2, 3 and 5.

During engagement of the stud with the socket, the socket-engaging part 6 is pressed through the aperture and the latch 11 snaps into engagement with the shoulder 13 to lock the stud and socket against separation when outward strain is exerted on the curtain 14 either above or at the sides of the stud. At the same time the embossed portion 5 of the closure plate 4 enters the socket-engaging portion and closely engages the wall 12 to assist in preventing separation of the fastener when strain is exerted upon the stud in a line transverse to the axis of the socket, as shown in Fig. 2.

Separation is effected in the same manner as described in the above-mentioned application. A pull on the lower edge of the curtain 14 initially moves the depending finger 15 which in turn releases the latch 11, as shown in Fig. 3, and continued pull on the curtain with the assistance of the spring 16 in the socket presses and tips the stud out of engagement with the socket. The stud is free to tip relative to the socket as soon as the spring urges the stud outwardly far enough for the sloping lower portion 17 of the socket-engaging portion to be opposite the wall 18 surrounding the stud-receiving aperture.

While I have shown and described a preferred embodiment of my invention, it will be understood that changes involving omission, substitution, alteration and reversal of parts, and even changes in the mode of operation may be made without departing from the scope of my invention, which is best defined in the following claims.

I claim:

1. A three-side lock fastener comprising, in combination, a socket having a stud-receiving aperture, a cooperating stud presenting a hollow non-resilient portion for passage into said aperture, attaching means for securing said non-resilient portion to a flexible support, a casing and a lever part pivotally located in said casing, said lever part presenting a latch extending into said hollow portion and out through a slot in the side wall.

thereof for locking the stud to the socket and a depending finger extending substantially parallel to the plane of the flexible support to be operated by an initial pull exerted upon the support to tip said lever and withdraw said latch into said hollow portion to permit separation of the stud from the socket.

2. A separable fastener comprising, in combination, a socket secured to a rigid support and presenting a stud-receiving aperture, a stud presenting a socket-engaging portion, attaching means for securing the socket-engaging portion to a flexible support, means carried by the stud for locking it with the socket against separation by outward strain on the flexible support at three sides of the stud and a spring-pressed closure plate in the socket presenting a boss entering a recess in the end of the socket-engaging portion to assist in preventing separation of the stud from the socket when lateral strain transverse to the axis of the socket is exerted upon the flexible support.

3. A separable fastener comprising, in combination, a socket having a stud-receiving aperture surrounded by a continuous wall, a shoulder behind said wall, and attaching means for securing the socket to a support, a cooperating stud having a non-resilient socket-engaging portion secured to a flexible support, a latch carried by said stud for engagement with said shoulder when said socket-engaging portion is entered into said socket to lock the stud to the socket, an aperture in the end of said socket-engaging portion and a spring pressed closure plate in said socket presenting a boss adapted to enter the aperture in said socket-engaging portion to assist in preventing separation of the fastener by strain transverse to the axis thereof.

4. A fastener stud including a non-resilient socket-engaging part, means for securing said part to a flexible fabric, a casing presented at the front face of said fabric, a latch pivoted in said casing and extending through one side of said socket-engaging part and a finger associated with said latch and extending from said casing at the front side of the fabric and being substantially parallel thereto thereby to be operated by initial movement of the fabric relative to the stud to withdraw the exposed portion of said latch into said socket-engaging part.

55 In testimony whereof I have signed my name to this specification.

DIDRICK DYRESEN.
